UNITED STATES PATENT OFFICE.

NORMAN FIELD HUTCHISON, OF BALWYN, NEAR MELBOURNE, VICTORIA, AUSTRALIA.

FILE FOR LOOSE SHEETS.

1,345,365.

Specification of Letters Patent.

Patented July 6, 1920.

Application filed April 10, 1918. Serial No. 227,635.

To all whom it may concern:

Be it known that I, NORMAN FIELD HUTCHISON, a subject of the King of Great Britain, and resident of Balwyn, near Melbourne, in 5 the State of Victoria and Commonwealth of Australia, have invented certain new and useful Improved Files for Loose Sheets, of which the following is a specification.

This invention relates to a paper file for 10 the purpose of holding loose sheets such as bills, circulars, letters, accounts and different forms of correspondence.

The object of the invention is to provide 15 a paper file which will be of greater utility than those at present in use.

The essential feature embodied in the invention consists in the use of clipping or holding means arranged on both sides of the backing or file support so that both sides of 20 the said support can be utilized for filing purposes.

In order that the invention may be more readily understood it will now be described 25 with reference to the accompanying drawings in which:—

Figure 1 is a front elevation, and

Fig. 2 is a view in end elevation, while—

Fig. 3 is a view in cross section of the improved file.

Fig. 4 is a view in perspective of the improved double clip forming an essential feature of the invention.

According to this invention the file consists of a solid supporting member *a* formed 35 of cardboard or other material being of any preferred shape but preferably rectangular as illustrated.

One end of the supporting member *a* is formed with a small hole *b* by means of 40 which it can be hung upon a nail, hook or the like.

The file clip consists of a spring clip formed in two spring loops *d*, *e*, the one loop *d* extending in spring tension along the 45 surface of one side of the support *a* while the other loop *e* extends in spring tension along the opposite surface of the said support *a*.

The support *a* is slotted at *f* to receive the portion *g* of the clip separating the two 50 spring loops *d*, *e*.

The clip loops *d*, *e*, may be circular as illustrated or they may be oval, elliptical, square, oblong, or any other shape desired.

In order to enable a bill, letter, or the like 55 to pass easily within the spring loops *d* or *e*, the receiving ends are given a slight turn outwardly as illustrated at *h*.

Both the spring loops *d*, *e*, are held by their own tension against the backing *a*, it 60 being obvious that the larger the number of sheets *i* filed, the greater will be the holding tension exerted.

A file constructed as above described will be of great utility, as a considerable saving 65 in cost and space is accomplished, and moreover, a greater number of sheets may be filed over the ordinary clip constructions at present in use.

What I claim as my invention and desire 70 to secure by Letters Patent, is—

A loose sheet supporting sheet having an elongated horizontal slot adjacent the upper edge thereof; and a spring clip comprising two coils connected together integrally at 75 their tops, the connecting portion of the clip passing through said elongated slot and engaging the lower edge of the slot whereby the clip is suspended from the lower edge of the slot, the coils of the clip having a normal 80 tendency to move toward each other to hold loose sheets placed under the coils to each side of the supporting sheet, the lower edge of each coil being straight and upturned to facilitate the entrance of the edges of loose 85 sheets between the supporting sheet and the coil.

Signed at Melbourne, in the State of Victoria and Commonwealth of Australia, this second day of March, A. D. 1918.

NORMAN FIELD HUTCHISON.
